COMBINED TELEPHONE LAMP BASE AND HOLDING TRAYS

Walter A. Moede, Naperville, Ill.

Application June 30, 1954, Serial No. 31,240

Term of patent 7 years

(Cl. D48—20)

Fig. 2

Fig. 1

Fig. 3

Figure 1 is a side elevational view of a combined telephone lamp base and holding trays showing my new design, the dotted lines illustrating a telephone base in attached position relative to the lamp base;

Figure 2 is a front elevational view thereof;

Figure 3 is a rear elevational view;

Figure 4 is a top plan view, the dotted lines representing a harp, socket and finial being omitted for convenience of illustration; and,

Fig. 4Fig. 5

Figure 5 is a fragmentary elevational view showing the side opposite Figure 1.

The dominant features of my new design are shown in solid lines. The dotted lines indicating a telephone in Figures 1 and 4 are for illustrative purposes only.

I claim:

The ornamental design for a combined telephone lamp base and holding trays, as shown and described.
